CLAIM

(30) **Foreign Application Priority Data**

The ornamental design for a folding table, as shown and described.

Oct. 19, 2006 (EM) 000607122

(51) **LOC (9) Cl.** **06-03**

FIG. 1 is a side view of a folding table in the open, ready-for-use position, in accordance with my new design;

(52) **U.S. Cl.** **D6/487; D6/488**

FIG. 2 is low perspective view thereof;

(58) **Field of Classification Search** D6/480–489, D6/495–499, 439–431, 423, 477–479; 108/150, 108/153.1, 155, 156, 161, 115, 118, 131, 108/129, 132; 248/188, 188.1, 188.8

FIG. 3 is high perspective view thereof;
FIG. 4 is a side view of the same folding table in the closed, ready-for-storage position;

See application file for complete search history.

FIG. 5 is a front view thereof; and,
FIG. 6 is a rear perspective view thereof.
